UNITED STATES PATENT OFFICE

SANFORD J. LOCKE, OF SYRACUSE, NEW YORK, ASSIGNOR TO UNITED STATES HOFTMAN MACHINERY CORPORATION, OF NEW YORK, N. Y., A CORPORATION OF DELAWARE

GARMENT PRESS

Application filed April 24, 1929. Serial No. 357,827.

This invention relates to pressing machines for garment pressing and laundry use.

An important characteristic of the invention is the fact that within the range of contact with the goods the head approaches the buck in a right line but above this range of movement swings in an arc. The result is accomplished by mounting the head-carrying lever with a pin and slot connection and providing it and the frame with coacting members which serve as an interfering stop to constrain the lever to a simple rocking movement until the lever is swung toward the head. At such point the stops clear each other and the head is thereafter guided in a right line motion toward the buck. The two successive motions so far described are preferably effected by a foot pedal which is latched in position at the termination of the second or right line motion. Thereafter pressure is applied through another instrumentality, preferably a power actuated toggle mechanism. The movement under the action of the last named mechanism is very slight and is an angular or swinging movement.

The preferred embodiment of the invention is illustrated in the accompanying drawings in which,

Figure 1 is a side elevation of the press with certain parts shown in section,

Figure 2 is a fragmentary section on the line II—II of Figure 1,

Figure 3 is a view similar to Figure 1 but showing the parts at the termination of the second or right line movement,

Figure 4 is a section on the line IV—IV of Figure 1, and

Figure 5 is a fragmentary section on the line V—V of Figure 3.

The mechanism is supported on a base frame 6 whose form is clearly shown in the drawing and may be varied according to the preferences of the designer. It includes brackets 7 to support the work table 8 and a support 9 of known form for a buck 11. This buck may assume any form known in the art, the one illustrated being intended as typical.

The frame 6 is preferably of a double or bifurcated form as illustrated and includes two upright members 12 which extend above the

table 8 at the rear of the press and terminate slightly above the upper surface of the buck 11. The members 12 are tied together by a fixed fulcrum bar 13 on which is mounted the bifurcated head-carrying lever or yoke 14. Each of the two arms of the yoke 14 is provided with a slot 15 formed in a reinforcing boss, the slot extending in a direction generally transverse to the lever;—that is to say at right angles to the pressing face of the head 16 which is carried by the lever into and out of pressing engagement with the head 11.

Formed on each arm of the yoke 14 and approximately beneath the slot 15 is an arcuate stop surface 17, the arc preferably being struck from the center of the bar 13 when this occupies the lower end of the slot 15, as shown in Figure 1. Each arcuate face 17 coacts with a mating arcuate face 18, each formed on a boss 19 carried by the corresponding portions 12 of the frame 6.

There is a journal bar 21 which extends between the arms of the yoke 14 and which is located at a point approximately midway between the slot 15 and the arcuate face 17. This bar 21 is connected by a bifurcated yoke or link 22 with a foot lever 23 to which the link is pivoted at 24.

The lever 23 is fulcrumed in the frame 6 at the rear thereof, the pivot being indicated at 25. The forward end of the lever is formed with a foot plate 26 and carries a spring urged latch 27 with foot actuated releasing arm 28. In the lower position of the lever 23 the latch 27 engages a keeper 29 on a portion of the frame 6. The lever 23 is urged in an upward direction by a coiled tension spring 31.

Also fulcrumed at 25 in the frame 6 is a lower link 32 of a toggle strut which also includes an upper link element pivoted at 33 to the upper end of the link 32.

The upper link is of known form being longitudinally compressible against spring resistance and being adjustable as to its effective length. It includes a bifurcated member 34 which is pivoted to the link 32 at 33 and through which is slidably a thrust rod 35.

The thrust rod 35 carries a spring seat 36

100

which is adjustable by means of a nut 37 and which reacts against the upper end of a spring 38 confined between the seat 36 and the upper end of the bifurcated member 34. 5 The upper end of the rod 35 is slidable through a pivot block 39 and is limited as to its longitudinal motion through the block by means of a lower collar 41 and an upper collar 42. The block 39 is mounted between the 10 rear portions of the arms of yoke 14 and is pivoted relatively to said yoke by means of trunnions 43. This arrangement provides a lost motion connection between the lever and the toggle mechanism, the purpose of which 15 will presently appear.

The toggle mechanism just described may be straightened and broken by a secondary toggle mechanism comprising a link 44, pivotally connected at its rear end at 44^a to the 20 member 32 of the first named toggle mechanism. Said link 44, at its forward end, is pivoted to the crank pin 45 of a crank shaft 46. This shaft is mounted in the bearings 47 formed in the frame member 6.

The crank shaft 46 may be rotated by any 25 suitable mechanism which is typified in the drawings by the motor 48 and transmission 49. This transmission is of a type for which no novelty is here claimed, comprising a worm reduction gear and a planetary train 30 including a sun wheel which may be locked against rotation to establish the drive train.

The mechanism for engaging the drive 35 train is illustrated as including a hand lever 51 connected to a link 52 so as to actuate the bell crank 53. The bell crank 53 carries a roller 54 which coacts with a control disk 55 on the shaft 46, the purpose being to cause the throw-out of lever 51 at definite positions 40 and to permit it to be actuated only when the shaft 46 is in definite positions.

Various mechanisms for accomplishing 45 this or equivalent results are known and any mechanism might be substituted which is capable of rotating the shaft 46 to the position in which the crank aligns with the link 44 and there arresting it, it being understood that after such arrest the motion of the crank 50 may be resumed at the will of the operator.

In order to secure the proper order of 55 manipulation in opening the press a gravity detent 57 is pivoted at 58 on the frame 6 and coacts with a lug 59 on the link or yoke 22. The detent 57 is provided with a tail or trip 61 which is engaged by a lug 62 on the link 44 on the releasing motion of the crank shaft 46, it being understood that this crank shaft 60 turns in the direction of the arrows in Figures 1 and 3.

A stop pin 57^a, fixed to the frame of the 65 machine, extends outwardly and is designed to contact the arm 57 to prevent the same from riding upwardly and off of the member 59 when the parts are in the position shown in Figure 3.

With a press constructed as above described the operator first places the goods to be pressed on the buck 11, he then depresses the pedal 26. This will exert, through the link 22, a swinging tendency to the lever 14. 70 The operator may, if he desires, draw the lever 14 down by hand but whether the operator merely depresses the pedal or whether he draws the lever down by hand a position will be reached (indicated in dotted lines in Figure 1) in which the arcuate member 17 clears the boss 19. At the same time the lost motion connection between the head carrying lever and the thrust toggle will permit the lever to come to the dotted line position just referred to. At this time the member 42 contacts the upper face of the member 39. When this point is reached the operator is enabled to draw the press head 16 downward in a straight line by further depressing the foot 25 pedal 26 until this is latched by the latch 27. When this has been done the parts will be in the full line position of Figure 3, at which time the member 41 contacts the under face of the element 39 so that the thrust toggle when straightened may exert pressure therethrough upon the head carrying lever.

Through this movement the control disk 55 is brought to a position where the operator is free to manipulate the lever 51, causing engagement of the drive train. As above set forth, this imparts motion to the crank shaft 46 which swings in the direction of the arrow until both toggles are straightened, as indicated in dotted lines in Figure 3. When the parts reach this position heavy pressure is exerted by the head upon the goods upon the buck and the drive train is automatically disconnected. Such pressure may be retained as long as desired but by manipulation of the lever 51 the drive may be again started to open the press.

It will be observed that the operator cannot kick the press off while under heavy pressure by releasing the latch 27, because even if the latch be released the detent 57 will hold the link 22 in its down position. However, as the crank shaft 56 rotates in the opening movement of the press and after the main toggle has been broken, thus relieving the pressure, the lug 62 will strike the tail 61 and release the detent 57. After this has been done the releasing of the latch 27 will permit the lever 23 to rise thus completing the opening movement of the press by first a vertical upward motion and then a swinging upward motion.

Obviously the invention may be embodied in various specific mechanisms but the one described is believed to be particularly advantageous.

What is claimed is:

1. The combination of a frame; a buck supported thereby; a head-carrying lever; a head carried thereby; a support for said head-car-

5 trying lever including a fulcrum member and interfering stops to constrain the lever to move in an arcuate path during a predetermined movement of the lever; means on said lever coacting with said member to afford pivotal movement thereof when said stops are in engaging relation and rectilinear movement of the lever with respect to the fulcrum member when said stops are in disengaged relation; a toggle mechanism interposed between the head-carrying lever and frame; means for moving said head through its arcuate and part of its right line motion to press closing position; means for locking the parts against press opening motion; and means for straightening said toggle.

2. The combination of a frame; a buck supported thereby; a head-carrying lever; a head carried thereby; a support for said head-carrying lever including a fulcrum member and interfering stops to constrain the lever to move in an arcuate path during a predetermined movement of the lever; means on said lever coacting with said member to afford pivotal movement thereof when said stops are in engaging relation and rectilinear movement of the lever with respect to the fulcrum member when said stops are in disengaged relation, as the lever is rocked about its pivot; a toggle mechanism interposed between said lever and frame; means reacting on said lever adjacent said means to impart an initial rocking movement to the lever, and through such movement to cause the interfering stops to clear; a latch for locking said last-mentioned means in substantially press closing position; and power operated means for straightening and breaking said toggle.

3. The combination of a frame; a buck supported thereby; a head-carrying lever; a head carried thereby; a support for said head-carrying lever including a fulcrum member and interfering stops to constrain the lever to move in an arcuate path during a predetermined movement of the lever; means on said lever coacting with said member to afford pivotal movement thereof when said stops are in engaging relation and rectilinear movement of the lever with respect to the fulcrum member when said stops are in disengaged relation; a toggle mechanism interposed between said lever and frame; operator operated means reacting on said lever adjacent said means to impart an initial rocking movement to the lever, and through such movement to cause the interfering stops to clear; power operated means for straightening and breaking said toggle; means for effecting connection between the power operated means and said toggle; cam means positioned by movement of the toggle towards press closing position to preclude said connection until the press has been closed; and a latch for holding said operator operated means in press closing position and arranged to be released

by the toggle breaking movement of the power actuated means.

4. In a press the combination of a fixed frame; a buck mounted thereon; a lever having a pin and slot connection with said frame between its ends; a head carried by one end of said lever for cooperation with said buck; a toggle reacting between the frame and the other end of said lever; stop means for restricting the lost motion of said pin and slot connection until the head has approached the buck; means for swinging said lever until said stop means clear and then drawing said lever, and the head carried thereby, toward the buck; means for locking the head in press closing position; and means for straightening said toggle.

5. In a press, the combination of a fixed frame; a buck mounted thereon; a lever having a pin and slot connection with said frame between its ends; a head carried by one end of said lever for cooperation with said buck; a toggle reacting between the frame and the other end of said lever; stop means for restricting the lost motion of said pin and slot connection until the head has approached the buck; means for swinging said lever until said stop means clear and then drawing said lever, and the head carried thereby, in a right line toward the buck; means for locking the head in press closing position, including an automatically engaging stop; means for straightening and breaking said toggle; and means operable by the toggle breaking movement of the last named means for releasing said automatically engaging stop.

6. In a garment press, the combination of a frame; a buck supported thereby; a head; a head-carrying lever; a support for said head-carrying lever including a fulcrum member and interfering stops to constrain the lever to move in an arcuate path during a predetermined movement of the lever; means on said lever coacting with said member to afford pivotal movement thereof when said stops are in engaging relation and rectilinear movement of the lever with respect to the fulcrum member when said stops are in disengaged relation; a thrust toggle having a lost motion connection with the rear portion of the head-carrying lever; and means for straightening the toggle.

In testimony whereof I have signed my name to this specification.
